CLAIM

We claim the ornamental design for a laptop stand, as shown and described.

DESCRIPTION

FIG. 1 is a top, perspective view of an embodiment of a laptop stand, showing our new design;

FIG. 2 is a bottom, perspective view thereof;

FIG. 3 is a front view thereof;

FIG. 4 is a rear view thereof;

FIG. 5 is a right side elevational view thereof;

FIG. 6 is a left side elevational view thereof;

FIG. 7 is a top plan view thereof; and,

FIG. 8 is a bottom plan view thereof.

Broken lines are for illustrating portions of the laptop stand which form no part of the claimed design.
